UNITED STATES PATENT OFFICE.

LEMUEL N. STEWART, OF AGENCY, MISSOURI, ASSIGNOR TO GEORGE H. FURBECK, OF ST. JOSEPH, MISSOURI.

ANCHOR.

977,757.

Specification of Letters Patent.

Patented Dec. 6, 1910.

Application filed March 5, 1909. Serial No. 481,230.

To all whom it may concern:

Be it known that I, LEMUEL N. STEWART, citizen of the United States, residing at Agency, in the county of Buchanan and State of Missouri, have invented certain new and useful Improvements in Anchors, of which the following is a specification.

This invention comprehends certain new and useful improvements in devices of that 10 type designed for use in anchoring the cables of suspension bridges, the guys of hoisting machines, or the like, and the invention has for its object a simple, durable and efficient construction of anchor which is 15 susceptible of being readily and positively expanded after having been embedded in position in the earth, so as to increase its bearing surface upon the latter, and hold the anchor effectually against any accidental 20 displacement, when subjected to excessive strain.

With this and other objects in view that 25 will more fully appear as the description proceeds, the invention consists in certain constructions and arrangements of the parts that I shall hereinafter fully describe, and then point out the novel features thereof in the appended claims.

For a full understanding of the invention 30 and the merits thereof, and to acquire a knowledge of the details of construction, reference is to be had to the following description and accompanying drawing, in which:

35 Figure 1 is a side elevation of an anchor constructed in accordance with my invention; Fig. 2 is a longitudinal section thereof; Fig. 3 is a detail perspective view, showing the upper ends of the arms in juxtaposition; and, Fig. 4 is a top plan view of the arms, illustrating the interlocking connection between the upper ends thereof.

Corresponding and like parts are referred 45 to in the following description and indicated in all the views of the drawing by the same reference characters.

A land anchor constructed in accordance 50 with my invention consists essentially of two separable anchoring arms 4 which are formed at their lower or rear ends with outstanding perpendicular flanges or flukes 5. The arms are formed at their upper or forward ends with pairs of inwardly disposed 55 spaced ears 6 which are interlocked so that one ear of each pair is positioned between

the spaced ears of the other pair. The said ears which are received between the spaced ears of the other pair, are termed the inner ears and are each formed with an outstanding pintle 8. The pintles 8 are arranged 60 upon the relative lateral movement of the arms in a direction to space the inner ears apart transversely in abutting relation to the respective outer ears, to be engaged in apertures 7 formed in the outer ears (see 65 Fig. 4). Pivotal connections are thus established between the adjacent inner and outer ears, it being noted that the pintles are disposed in transverse alinement, whereby the arms are associated for free turning movement about a transverse axis. 70

A rod serving as the shank or stem 1 of the anchor is arranged to be inserted between the inner ears and serves to maintain the same spaced apart sufficiently to retain 75 the pintles 8 in the apertures 7, whereby to prevent the anchoring arms 4 from becoming accidentally disconnected. At its forward or upper extremity the shank is bent into the form of an eye 2 for the attachment 80 of a guy wire or the like. Below this eye the shank is threaded, as indicated at 3, a nut 9 being positioned at the forward end of the threaded portion and being arranged in front of the interlocked ears 6 and abutting 85 against the same to serve as a stop to limit the rearward longitudinal sliding movement of the shank therethrough. A washer 10 is preferably mounted on the shank between the nut and the ears to relieve 90 the parts of wear.

The rear end portion of the shank passes freely through an opening 11 formed at the apex of a framelike wedge 12 which is interposed between the free ends of the anchoring arms 4, the shank being also adapted to be accommodated in a second opening 11 formed in the base of the wedge in longitudinal alinement with the opening through 95 the apex. The legs of the wedge are received in and guided by recesses formed in the inner or adjacent edges of the flukes 5 (see Figs. 1 and 3). A nut 13 works upon the threaded portion 3 within the framelike wedge and bears against the apex thereof and is fitted snugly between the legs of the wedge so as to be held thereby against 100 any relative turning movement. 105

In the practical use of my improved anchor, the same is placed in a suitable hole 110

or excavation in the earth or cement or the like, in the usual manner, with the forward end of the shank 1 projecting therebeyond. A bar or other suitable tool is then inserted 5 in the eye 2, and the shank is turned in the requisite direction, but inasmuch as the stop 9 prevents the shank from moving rearwardly between the arms 4, it will be manifest that this movement works the nut for- 10 wardly upon the threaded portion 3, which thus draws the wedge between the arms 4 to spread the same apart and effect the expansion of the anchor and increase the bearing surface thereof upon the earth. After this 15 operation is completed, the cable or guy rope is attached to the eye 2, and it will be seen that by virtue of the arrangement just described, it will be securely maintained in position against any loosening even when 20 subjected to excessive strain.

From the foregoing description, in connection with the accompanying drawing, it will be apparent that I have provided an improved anchor which is adapted for use 25 in securing the ends of cables or guy ropes, or for other purposes generally; which is susceptible of being conveniently expanded after having been placed in position; which embodies to a marked degree the characteristics 30 of simplicity, durability and efficiency in construction and operation, and which consists of comparatively few parts that may be easily and cheaply manufactured and readily assembled.

Attention is particularly directed to the fact that by removing the wedge 12 and the nut 13 from the rear portion of the shank, the latter may be withdrawn from between the interlocked ears, whereby to permit the 40 anchoring arms to be shifted laterally to withdraw the pintles from the corresponding apertures 7. The disconnection of the arms may thus be accomplished with facility when occasion demands, so that the 45 anchor may be completely "knocked down" and its parts stowed away within a small compass, as is manifestly desirable for shipping purposes or the like.

Having thus described the invention, what 50 I claim is:

1. A land anchor including separable anchoring arms formed at one end with pairs of spaced ears interlocked with one ear of each pair positioned between the ears of the 55 other pair, one ear of each pair being

formed with a pintle pivotally engaged with the adjacent ear of the other pair upon the relative lateral movement of the arms in one direction to space the innermost ears apart, a removable shank passing between the innermost ears of the interlocked pairs and maintaining said innermost ears spaced apart to hold the arms in pivotal association against separation, and means for spreading apart the free ends of said arms. 60

2. A land anchor including separable anchoring arms formed at one end with pairs of spaced ears interlocked with one ear of each pair positioned between the ears of the other pair, one ear of each pair being 70 formed with a pintle pivotally engaged with the adjacent ear of the other pair upon the relative lateral movement of the arms in one direction to space the innermost ears apart, a removable shank passing between the innermost ears of the interlocked pairs and maintaining said innermost ears spaced apart to hold the arms in pivotal association against separation, the shank being movable longitudinally between the ears, a 80 means carried by the shank for spreading apart the free ends of said arms by and upon the relative longitudinal movement of the shank. 75

3. A land anchor including separable anchoring arms formed at one end with pairs of spaced ears interlocked with one ear of each pair positioned between the ears of the other pair, one ear of each pair being formed with a pintle pivotally engaged with the adjacent ear of the other pair upon the relative lateral movement of the arms in one direction to space the innermost ears apart, a shank passing between the innermost ears of the interlocked pairs and maintaining 90 said innermost ears spaced apart to hold the arms in pivotal association against separation, attaching means provided at one end of the shank, and means carried at the other end of the shank for spreading apart 95 the free ends of the arms, said spreading means being detachable from the shank to permit the same to be withdrawn from between the ears. 100

In testimony whereof I affix my signature 105 in presence of two witnesses.

LEMUUEL N. STEWART. [L.S.]
